UNITED STATES PATENT OFFICE

2,609,116

SHUTTLE CAR

William R. Beck, Chicago, Ill., assignor to Goodman Manufacturing Company, Chicago, Ill., a corporation of Illinois

Application September 1, 1950, Serial No. 182,745

3 Claims. (Cl. 214—83.36)

1

This invention relates to a shuttle car particularly adapted for the transportation of bulk materials such as in the mining of coal. As the name indicates, a shuttle car with which this invention is concerned is adapted for moving back and forth between a receiving point such as a coal loading machine and a discharging point such as a mine car or conveyor.

This invention is concerned specifically with improvements in the type of shuttle car disclosed in Patent No. 2,192,650, issued March 5, 1940 to John D. Russell.

The above-mentioned type of shuttle car has an elongated body with relatively wide and narrow compartments at the rear and front, respectively. A longitudinally movable chain and flight conveyor runs along the bottom to facilitate loading and to make possible unloading. When filled, material is mounted high above the body, ordinarily as much as can be piled on without spillage during movement to the discharging point. Since the narrow compartment is at the front or discharge end of the body all the material in the relatively wide rear compartment must be moved through it. In the conventional shuttle car spillage during unloading at the discharge point has heretofore been considered unavoidable because unloading movement of the conveyor imparts some forward movement to all the material in the relatively wide rear compartment, causing some of the material, initially, to be spilled over the sides of the narrow compartment. This, of course, makes extra clean up work to control the height of the pile of spilled material. With the present invention the above-mentioned spillage and the clean up work made necessary thereby are entirely eliminated by upstanding guide or baffle formations on the angular sides defining the wide compartment which function to direct the pile of material therein downwardly, into the wide compartment, as it is unloaded by the conveyor. Other objects and advantages will be seen in the following description taken in connection with the drawings in which:

Figure 1 is an isometric view of a shuttle car illustrating a preferred embodiment of the present invention;

Fig. 2 is a fragmentary plan view of the car shown in Fig. 1;

Figs. 3, 4 and 5 are longitudinal sectional views of the car showing different stages in loading during which material is mounted high atop the car; and

Fig. 6 is a transverse, cross-sectional view of Fig. 2, taken along line 6—6.

Referring now more specifically to the embodiment shown in the drawings, the shuttle car comprises a body 21 having transversely spaced longitudinally extending side walls 22 defining a receiving compartment 23 and a discharge compartment 24 at the rear and front, respectively, of the car. The bottom of the body comprises a chain and flight conveyor 26 adapted to be moved forwardly to facilitate loading of the car and to make possible unloading. The forward portion of the discharge compartment 24 comprises an elevating section defined between a pair of side walls 27 which are pivoted for up and down movement about a transverse axis indicated at 28 in Fig. 3. By this construction in which the discharge compartment is relatively narrower an operator's control compartment 29 and a motor or control box 31 may be installed within the overall width limits of the car. Rubber tired wheels 32, in this instance, are provided for carrying the body and the body may be supported thereon in any suitable manner. The relatively wide receiving compartment 23 is defined by a pair of side walls 33 which are angularly inclined upwardly and outwardly from the conveyor 26. A minor upstanding cusp or convexity 34 is provided to make room for the rear wheels 32.

So far the structure described is conventional and is described in considerably more detail in the above-mentioned patent.

It will be apparent that, with the conventional structure only as above-described, when the body is piled high with coal, for instance, and the conveyor 26 is moved forward to discharge the coal, the entire mound of coal in the receiving compartment will be given a forward motion. This forward motion, of course, will be at its greatest speed at the center and will be much slower at the sides. However, before the pile has been reduced in height below the top edge 35 of the body some of it along the side walls 33 will be moved forwardly and spilled off onto the ground at the sides of the discharge compartment or into the operator's control compartment.

By the present invention the above-mentioned spillage is entirely eliminated through the use of transverse upstanding baffle plates or guides 36 which prevent forward movement of that part of the pile supported on the side walls 33 and guides it downwardly onto the conveyor after the latter has removed the central portion of the load. Each of the baffles 36 is formed of a pair of similarly shaped plates 36a, 36a welded together along a common apex line 36b and welded to one or the other of the side walls 33 along longitudinally spaced lines 36c. Thus, in

the present instance, each formation 36 presents a triangular cross section for strength.

A further feature of the invention is best shown in Fig. 6, where the inner end portions 35 of the baffles actually extend into the receiving compartment area above the conveyor 26. By this arrangement, longitudinal movement of the load of material, responsive to movement of the conveyor, is effectively resisted along the side-walls 33 and is confined to that portion of the material above the conveyor, as indicated, for example, by broken lines A, B and C for different load conditions.

In operation, when used with a coal loading machine, for example, the shuttle car may be loaded as shown in Figs. 3, 4 and 5.

To begin the loading operation the shuttle car will be moved under the loading machine discharge boom 37 so that the end of the boom is forward of the forward motion baffle formation 36. Preferably, the end of the boom will be near the forward portion of the receiving compartment 23. The loader boom conveyor is then operated to make an initial pile of coal between the receiving and discharge compartments as indicated at 38 in Fig. 3.

Then, without changing the relative positions of the shuttle car or loader boom, the operator will inch the conveyor 26 slowly backward while coal is being received until the pile of coal reaches the front of the car with a contour as designated 39 in Fig. 4.

During the final loading stage the shuttle car itself will be inched away from the loader to completely fill the car with coal, having a contour as designated 41 in Fig. 5. The pile of coal on the loaded shuttle car then completely buries the baffles 36 and is mounted high above the top edges of the side walls as also shown in Fig. 5.

The shuttle car is then moved forward to its discharging point (not shown) where the operator elevates the forward section 27 suitably and starts the conveyor 26 moving in a forward and discharging direction as indicated by the arrows 42 in Fig. 2. This empties the car first by dragging out the central part of the load above the conveyor during which time the load at the sides resting against the walls 33 is blocked against forward longitudinal movement by means of the guide formations 38. Since the center part of the pile is lower than part on the sides moves inwardly and downwardly in the direction of arrows 43 (Fig. 2) to join the material being discharged at the front of the car.

While one form in which the present invention may be embodied has been shown and described it will be understood that various modifications and variations thereof may be affected without departing from the spirit and scope of the invention as defined by the appended claims.

I claim:

1. In a shuttle car, the combination of a material receiving body having two side walls extending substantially the full length of said body and defining receiving and discharge compartments, and a conveyor forming the bottom of said body and adapted to discharge material from the forward end of said body, at least a portion of said side walls in the receiving com-

partment being angularly inclined upwardly and outwardly from the edges of the conveyor whereby the receiving compartment is of greater width than the discharge compartment, said angularly inclined side wall portions having upstanding material guiding baffle formations extending into that portion of the receiving compartment above the conveyor and effective to resist longitudinal movement of material therealong responsive to movement of the conveyor from the receiving to the discharge compartments.

2. In a shuttle car, the combination of a material receiving body having two side walls extending substantially the full length of said body and defining receiving and discharge compartments, and a conveyor forming the bottom of said body and adapted to discharge material from the forward end of said body, at least a portion of said side walls in the receiving compartment being angularly inclined upwardly and outwardly from the edges of the conveyor whereby the receiving compartment is of greater width than the discharge compartment, said angularly inclined side wall portions having transverse upstanding baffle plates thereon spaced from the entrance to the discharge compartment and having a transverse spacing between their inner ends less than the width of the side walls of the discharge compartment, whereby said baffle plates are effective, when the conveyor is running, to direct flow of material, which is against said inclined side wall portions, transversely downward toward the conveyor as the latter is operated to move material longitudinally of the body.

3. In a shuttle car, the combination of a material-receiving body having two side walls extending substantially the full length of said body and defining receiving and discharge compartments, a longitudinally extending conveyor at the bottom of said body and adapted to move material from said receiving compartment and through the discharge compartment, at least a portion of said side walls in the receiving compartment being angularly inclined upwardly and outwardly from the edge of the conveyor whereby the receiving compartment is of greater width than the discharge compartment, said angularly inclined side wall portions having upstanding material-guiding baffle formations spaced from the juncture between said compartments and extending into the area above the conveyor in said receiving compartment and being effective to resist longitudinal movement of material therealong for confining said longitudinal movement of said material by the conveyor to that portion of the material above the conveyor.
